ABSTRACT OF THE DISCLOSURE

Detonating fuse cord having along its length alternating sections of greater and lesser explosive energy is manufactured by forming dry particulate explosive into a core about a centre threadline in such a manner that the core is made up of connected sections of greater and lesser explosive mass. The core is thereafter enveloped with a protective covering.

This invention relates to detonating cord and in particular, to the manufacture of a detonating cord having an explosive core of alternating core sections of controlled variations. Such a detonating cord has particular use in, for example, metal expansion applications.

As is known in the explosives art, detonating cords are normally produced in long or continuous lengths and comprise essentially a uniform core of explosive encased in a protective wrapping or sheath. Originally, the protective sheath consisted of a soft metal such as lead but these lead sheathed cords have now generally been superseded by those having sheaths consisting of water resistant tape or textile wrappings, synthetic plastics and the like. The amount of explosive per foot of length in the core may vary from a small quantity of from 0.1 to about 10 grains, as in low energy detonating cord (LEDC), to as much as 50 grains or more. Typical explosives employed as core material are, for example, pentaerythritoltetranitrate (PETN), cyclotrimethylenetrinitramine (RDX), nitromannite, lead azide, trinitrotoluene (TNT), cyclotetramethylenetrinitramine (HMX), lead styphnate or tetryl and mixtures of these.

In the explosives industry detonating cords are manufactured by one or other of the dry or wet processes. In the dry process relatively coarse, particulate, dry explosive which comprises the core material of the cord is encased in a continuous column by means of a wrap of tape-like material and thereafter encircled by means of textile yarns or the like. The cord may thereafter be coated with a waterproofing surface layer of pitch, thermoplastic or the like. The dry process is normally employed in the manufacture of detonating cords having a core load of 25 grains or more of explosive per foot of length.

In the wet process, the core is formed from a thickened aqueous slurry of particulate explosive which is wrapped and covered in much the same manner as that employed in the dry process. Generally the wet process is employed in the manufacture of detonating cord having a core load of 4 grains or more of explosive per foot of length.

It has heretofore been the object and concern of the explosives industry to manufacture detonating cords having an absolute minimum of core load variation throughout the cord length in order to ensure constant detonation characteristics along the cord, in particular, uniform lateral energy output. It has now been found that in certain applications such as metal expansion, it is desirable to provide a detonating cord having an alternating or pulsating lateral energy output with a substantially constant linear velocity of detonation.

2

Accordingly, it is an object of the present invention to provide a method of manufacture of detonating cord wherein the cord contains a continuous explosive core load, which core load comprises alternating sections of greater and lesser explosive energy.

Other objects of the invention will become obvious from a consideration of the following disclosure and claims.

The novel method of manufacture of the invention comprises the steps of directing a stream of dry particulate explosive through an orifice and enveloping the stream with a wrapping means in such a manner that regular, alternating sections of the resulting explosives column have different energy outputs.

The method of the invention and the product thereof may be more fully understood by reference to the accompanying drawings wherein:

FIG. 1 is a sectional view of one embodiment of a finished detonating cord made by the method of this invention.

FIG. 2 is a sectional view of a second embodiment of a finished detonating cord made by the method of this invention;

FIG. 3 is an elevational diagrammatic view of a portion of an apparatus suitable for use in the method of the invention; and

FIG. 4 is an elevational diagrammatic view of an alternative arrangement of an apparatus suitable for use in the method of the invention.

Referring in detail to FIG. 1, there is shown a detonating cord 1 having an inner threadline 2. Threadline 2, made of twisted or braided cotton, linen or the like, comprises alternating thick and thin sections shown as 3 and 4 respectively. Explosive charge 5 surrounds threadline

2 and assumes the shape of interconnected heavy and light explosive sections 6 and 7 respectively. Explosive charge 5 is enveloped by a wrap of paper tape or the like 8 and an overlay of filament wraps 9 and the whole has an outer covering 10 of, for example, a flexible thermoplastic material.

Referring to FIG. 3, there is shown an apparatus which may be employed to manufacture the detonating cord of FIG. 1 and which comprises a center thread, gravity feed fuse making apparatus well known in the art. In operation, a medium fine to very fine granular explosive such as PETN, from a storage hopper is continuously delivered by feed means 11 into a tapered funnel-shaped hopper 12. A cord or thread 13 having alternating thick and thin sections 3 and 4 is passed from a source (not shown) continuously downward through the neck 14 of hopper 12. The passage of thread 13 through hopper 12 and the granular explosive contained therein, carries the explosive through neck 14 in alternating quantities in cooperation with the thick and thin sections of thread 13. As the thread and explosive emerges from neck 14 in columnar form of constant diameter it is enveloped by a tape 15 of, for example, paper or plastic and thereafter overwrapped by textile threads 16 and 17 located on textile spinning head 18. The semi-finished cord is then passed over pulley 19 and forwarded to an outer protective sheath application station (not shown) after which it may be wound on a take-up spool for storage or shipment.

Referring to FIG. 2, there is shown a detonating cord 20 having an inner explosive core 21 comprised of a filament wrapped column of detonating cord having a core load of, for example, 25 grains of PETN per linear foot. Additional quantities of PETN explosive 22 surround core 21 in spaced-apart sections along the length of core 21. Core 21 and added explosive sections 22 are enveloped by a tape of paper or plastic 23 and an overlay of filament yarn 24 and the whole has an outer covering 25 of, for example, a flexible thermoplastic material.

Referring to FIG. 4, there is shown an apparatus which may be employed to manufacture the detonating cord of FIG. 2. The apparatus shown in FIG. 4 comprises, in general, a well known type of center thread, gravity feed, fuse making device but which has been modified for purposes of the method of the invention. In operation, an unsheathed, filament-wrapped detonating cord 30 comprising, for example, 25 grains of PETN per linear foot, is continuously fed from a source (not shown) downward through the neck 31 of funnel-shaped hopper 32. The opening in neck 31 is slightly larger than the space occupied by cord 30. A medium fine to very fine granular explosive 33 such as PETN is delivered in alternating, measured quantities by feed means 34 into hopper 32. Cord 30 together with the delivered portion or "slug" of PETN 33 pass through the neck 31 where they are immediately wrapped by tape 35 and thereafter overwrapped by textile threads 36 and 37 located on textile spinning head 38. The semi-finished cord is then passed over pulley 39 and forwarded to an outer protective sheath application station (not shown) after which it may be wrapped on a take-up spool for storage or shipment.

The core sections of greater and lesser quantity of explosive which may take the form of thick and thin sections of finished cord, as shown in FIG. 2, or which may take the form of a cord of constant external thickness about a centre threadline, as shown in FIG. 1, may be made in any desired combinations by varying the steps of the method. In using the apparatus of FIG. 3, for example, the centre thread or cord 13 may be constructed in a range of thicknesses or length in its sections 3 and 4 and, at the same time the size of neck 14 may be altered to allow more or less of the explosive to emerge from hopper 12. In using the apparatus of FIG. 4, for example, the core load of the center fuse-cord 30 may be varied as may be the quantity of explosive 33 deposited into hopper 32.

It will be obvious from the foregoing description that detonating core comprising alternating connected sections

of greater and lesser explosive energy may also be produced through the use of, for example, explosives having different energy values or strengths. That is to say, the continuous column of light core 21 in FIG. 2 may comprise, for example, PETN while the added explosive in the heavy section 22 may comprise, for example, TNT.

We claim:

1. A method of continuously producing detonating fuse cord having along its length alternating sections of different potential energy outputs, comprising the steps of:
  - (a) providing high explosive material in dry particulate form,
  - (b) depositing the high explosive material about axially spaced apart sections of an unsheathed detonating cord of constant diameter and
  - (c) enveloping the high explosive material with a covering as it is deposited on the cord.
2. A method as claimed in claim 1 wherein the dry particulate high explosive is selected from the group consisting of pentaerythritoltetranitrate, cyclotrimethylenetrinitramine, nitromannite, lead azide, trinitrotoluene, cyclo-tetramethylenetrinitramine, lead styphnate, tetryl and mixtures of these.
